UNITED STATES PATENT OFFICE.

CLIFFORD SANFORD ELFELT, OF LOS ANGELES, CALIFORNIA, ASSIGNOR TO ESTHER ELFELT AND DAVID WEBER, BOTH OF CHICAGO, ILLINOIS.

HAND BAG.

Application filed May 16, 1921. Serial No. 470,134.

To all whom it may concern:

Be it known that I, CLIFFORD SANFORD ELFELT, a citizen of the United States, residing at Los Angeles, in the county of Los Angeles and State of California, have invented certain new and useful Improvements in Hand Bags, of which the following is a specification, reference being had to the accompanying drawings, and to the reference characters marked thereon, which form a part of this specification.

This invention relates to improvements in hand bags, vanity boxes and the like.

Ladies commonly carry small hand-bags in which are contained a variety of toilet articles and a mirror, the latter being usually positioned in the hinged lid of the box or container. It frequently happens that it is desirable to make use of the toilet articles in darkened places, such for example as a theatre or a taxi-cab, where illumination is impossible or practically so.

The principal object of my invention, therefore, is to provide a hand bag with a lamp of such size and location as to illuminate the face of a person who is looking into the mirror of the bag, casting sufficient light for all practical purposes and yet have the lamp rays so concentrated and so relatively dim that when the device is used in a theatre or other place normally dark, the attention of neighbors will not be disturbed or distracted thereby.

Another object of the invention is to produce a device of the character described, which will be neat, efficient for its intended purpose and have no complicated parts to get out of order; one which will permit of replacement of the lamp or of the battery or both when exhausted in use and in which the working parts will be so covered and protected as not to mar the beauty of the interior of the structure nor interfere in any way with its other functions and utility.

These and other objects and advantages will be manifest as I proceed with the description of the invention, which consists of the devices and combinations of devices herein illustrated and described and more particularly pointed out in the claims appended thereto.

In that form in which I have chosen to illustrate my invention in the accompanying drawings,

Fig. 1 is a view in perspective of a ladies' hand-bag, with the lid opened.

Fig. 2 is a vertical, transverse, sectional view illustrating certain details, and

Fig. 3 is a perspective view, upon a different scale, showing the lamp circuit, the lamp and a dry cell or battery.

Referring to said drawings, the hand-bag is indicated as a whole by the letter A, the body being composed of a bottom 1, end walls 2, 2, a front wall 3 and a rear wall 4; said body forming an open top compartment suitable for the reception of toilet and other articles. This compartment is closed by a top or lid member 5, hingedly connected along its rear margin to the top margin of the rear wall 4 by any suitable hinge device, such for example as the strap 6. Within the recess of the lid member 5 is a mirror 7, secured in the usual manner.

8 indicates a miniature lamp supported in a lamp socket 9, secured to the angularly disposed arm or plate 9^a, the lamp lens projecting through a suitable aperture in the inclined wall 10. A metal conductor strip 11 is secured to the inside of the back wall 4 in such position as to be in contact with the terminal end of the lamp 8, the lower end of the strip 11 being in contact with the resilient terminal strip 12 of a dry cell or battery 13. The other terminal strip 14 of the battery 13 may similarly contact with a resilient conductor strip 15.

A conductor plate 16 is secured to the back wall 4, and is in contact with the socket holding arm 9^a and with the conductor strip 15. A switch, which in this instance is a pin 17 movably mounted in the slotted plate 18, is located in such position as to permit, in one position, its inner end to be free from and in another position to be in contact with the yielding conductor strip 15. This strip 15 is so bent and so located as to close the electric circuit when its lower end bears against the terminal strip 14, and to break the circuit when forced out of contact with terminal 14 by the pin 17. In Fig. 3, the full lines indicate the closed circuit, while the dotted lines indicate the position of the pin 17 and strip 15 when the circuit is open.

The dry cell or battery 13 is suitably enclosed and held in its proper position by a suitable casing 19. A vertical wall 20 joins the casing to the inclined wall 10. The cas-

ing 19 is provided, preferably, with a foldable end flap 21, which folds down over and is locked to an upwardly folding flap 22, by any suitable snap fastening device, such, for example, as the stud and ring indicated at 23. These flaps 21 and 22 are separated and opened out, as indicated by dotted lines in Fig. 2, to expose the interior of the casing 19, and after a dry cell 13 has been inserted 10 in position, these flaps 21, 22, are brought together, as indicated in full lines, and thus lock or hold said dry cell in its proper position.

It will be observed that the angular position of the arm 9 and of the wall 10, are such that when the lamp 8 is in place and the switch 17 moved to cause the strip 15 to contact with the terminal 14 and close the circuit, the light rays will project not only 20 in a direction away from the mirror 7 but in a direction best calculated to strike the face of a person who may be looking into the mirror. Thus it will be understood that the face is illuminated properly and will be 25 so properly reflected in the mirror as to permit the user to inspect the face and apply the toilet article thereto.

It will be understood that the lamp 8 will be of a size which will give out light rays 30 sufficient to illuminate the face of the user and yet be sufficiently concentrated so as not to annoy others by a general illumination. The lamp is not positioned or intended to illuminate either the mirror or the interior 35 of the bag compartment, but the face of the user. Hence the importance of positioning the lamp with its central longitudinal axis normal to the surface of the inclined member 10, which member is in a predetermined 40 position with respect to the mirror. I have referred to the mirror as hinged or in the hinged lid, but the mirror may not be hinged, in which event the lamp 8 must be 45 so positioned as to throw its light rays upon the face of the user and not into the mirror.

The style and size of the hand bag or container and the current supplying medium, whether one dry cell or a plurality of cells, will of course make some slight difference in the size and location of the terminal and may necessitate corresponding shifting of the conductor strip to complete the circuit. These and other changes are within 50 the range of the mechanic and all such I desire to be comprehended within the scope 55 of my invention, and therefore my invention is not limited to the specific form and arrangement hereinabove described and illustrated, excepting as set forth in the 60 claims appended hereto.

It will be observed that there are no complicated parts to get out of order and that operation and maintenance are very simple.

I have shown a reflector 24 surrounding 65 the lamp 8. I find this is highly advan-

tageous. In the form illustrated the reflector is integral with the socket 9, but manifestly may be otherwise constructed.

While I have shown my invention as applied to a hand-bag, it will be understood 70 that it is equally applicable to vanity boxes and other articles used by ladies in which to carry mirrors and other toilet articles.

I claim as my invention:

1. In a device of the character described, 75 the combination with a compartment having a rear wall, a lid hinged thereto and a mirror in the lid, of a lamp socket, an arm support therefor angularly secured to the rear wall, a lamp in the socket, a pair of flexible, 80 conducting strips secured to the rear wall, one electrically connected with the lamp and the other with the lamp socket, a dry cell or battery in the compartment, its terminals being for contact with the two conductor 85 strips, a slotted plate, a switch pin movable therein and adapted in one of its positions to disconnect one of the flexible conductor strips from its battery terminal, and a casing or cover for the lamp parts and battery, 90 the lamp lens and the switch pin being operatively exposed through said casing.

2. In a device of the character described, 95 the combination with a compartment having a rear wall, a lid hinged thereto and a mirror in the lid, of a lamp socket, an arm support therefor angularly secured to the rear wall, a lamp in the socket, a pair of flexible 100 conducting strips secured to the rear wall, one electrically connected with the lamp and the other with the lamp socket, a dry cell or battery in the compartment, its terminals being for contact with the two conductor strips, a slotted plate, a switch pin movable 105 therein and adapted in one of its positions to disconnect one of the flexible conductor strips from its battery terminal, and a casing or cover for the lamp parts and battery, the lamp lens and the switch pin being operatively exposed through said casing, and 110 means on the casing for removably locking the battery in position.

3. In a device of the character described, 115 the combination with a compartment having a rear wall, a lid hinged thereto and a mirror in the lid, of a lamp socket, an arm support therefor angularly secured to the rear wall, a lamp in the socket, a pair of flexible 120 conducting strips secured to the rear wall, one electrically connected with the lamp and the other with the lamp socket, a dry cell or battery in the compartment, its terminals being for contact with the two conductor strips, a slotted plate, a switch pin movable 125 therein and adapted in one of its positions to disconnect one of the flexible conductor strips from its battery terminal, and a casing or cover for the lamp parts and battery, the lamp lens and the switch pin being operatively exposed through said casing, and 130

means on the casing for removably locking the battery in position, said means including interlocking flaps.

4. In a device of the character described, 5 the combination with a compartment having an inside wall and a mirror hinged thereto, of means for mounting an electric lamp adjacent to the mirror with its lens facing angularly and away from the mirror, means for supplying current to the lamp, a switch for controlling the current, 10 said mounting means comprising an in-

clined member secured to a wall of the compartment, and a reflector associated with the lamp.

15

In testimony that I claim the foregoing as my invention I affix my signature, in the presence of two witnesses, this 14th day of May, 1921.

CLIFFORD SANFORD ELFELT.
